J. W. BRUNDAGE,
PLAITING MACHINE,
APPLICATION FILED JUNE 4, 1920.

1,371,853.

Patented Mar. 15, 1921.

By Oscar Middleton Donaldson & Hall
Attorneys.

UNITED STATES PATENT OFFICE.

JAMES WILLIAM BRUNDAGE, OF AKRON, OHIO, ASSIGNOR TO THE MILLER RUBBER COMPANY, OF AKRON, OHIO, A CORPORATION OF OHIO.

PLAITING-MACHINE.

1,371,853.

Specification of Letters Patent. Patented Mar. 15, 1921.

Application filed June 4, 1920. Serial No. 386,526.

To all whom it may concern:

Be it known that I, JAMES W. BRUNDAGE, a citizen of the United States, and resident of Akron, Ohio, have invented certain new 5 and useful Improvements in Plaiting-Machines, of which the following is a specification.

My present invention relates to an improved plaiting machine or apparatus and 10 is designed for the purpose of ornamenting various articles made of thin rubber by plaiting or gathering, puckering or corrugating the material and at the same time attaching to the material a band of rubber in 15 a simple and expeditious manner.

The machine is particularly designed to accomplish this work around the limb and waist openings of rubber diaper covers but 20 obviously it may be used for similar ornamentation of other articles of wearing apparel.

The invention comprises the novel combination of elements and also the arrangement of parts as hereinafter described, the 25 nature and scope of my invention being defined by the claims appended hereto.

An embodiment of my invention is illustrated in the accompanying drawings in which,—

30 Figure 1 is a plan view of a machine or apparatus such as referred to.

Fig. 2 is a side elevation, and

Fig. 3 is an end elevation.

Referring more particularly to these 35 drawings the essential parts of the apparatus comprise a corrugated roller or cylinder 7 having corrugations entirely across its face, and a second roller or cylinder formed of two corrugated portions 8, having corrugations which coact with cylinder 7, but the sum of whose faces is less than the face 40 of the cylinder 7, and having a plain cylindrical portion located between them. The plain portion 11 is of such a diameter that

45 when the corrugated portions 7 and 8 are in proper mesh or engagement the surface of portion 11 will closely approach the top of the corrugations of 7. If a band of uncured rubber compound similar to dental

50 dam rubber and wider than the face of portion 11 be fed through between the described rollers or cylinders, it will be fluted or gathered in accordance with the shape of the corrugations and if at the same time, a 55 second strip of the same or similar material

but less in width than portion 11 be fed through the device substantially central as to the portion 11, the second strip will not be fluted or gathered, but will be united to the first strip at intervals where the tops of the 60 corrugations on cylinder 7 press the two strips together against the portion 11.

In my preferred embodiment of the invention as illustrated in the drawings I have shown the corrugations in the cylinders or 65 rollers as in the shape of intermeshing or coacting gear teeth adapted to form parallel plaits or folds in the material operated on but it will be understood that by the term corrugated I include any form of intaglio 70 and relief which will produce a puckered or wrinkled and hence ornamental surface, the design being capable of being changed to suit individual tastes without departing from the spirit of my invention. 75

In operating upon such articles as diaper covers, in the manufacture of which it is desirable to place such ornamentation around the edge of openings, it is necessary to provide means for separating the two cylinders 80 so as to admit and remove the garment. To accomplish this in the form shown, I have mounted the cylinder 7 upon a shaft 12 disposed in rigid bearings in the main frame 1 and have mounted the cylinder 8 upon a 85 shaft 14, parallel to shaft 12 and journaled in bearings in a swing frame 21 pivoted on a horizontal shaft 15 journaled in bearings in the posts 1^a of the main frame of the machine. A spring 9 serves to normally separate the two cylinders so that the material 90 acted upon may be inserted or removed and a foot treadle 2 connected by rod 2^a to the swing frame is used to exert the necessary pressure to bring the rolls together. An adjustable stop 3 limits the pressure which 95 may be applied.

I have also provided a pair of ordinary spur gears 4 and 5 on shafts 12 and 14, which mesh together and drive the shafts at 100 the same speed; these gears prevent the material from being subjected to the driving strain and being crushed thereby or ruptured.

The shaft 14, also carries a worm gear 22 105 by means of which the shaft is driven. A worm 23 is mounted in position to mesh with the worm gear 22 and is in turn driven by a motor through clutch 24. An auxiliary roller 18 is mounted on a swing frame 17, 110

which is pivoted on swing frame 25, the roller being supported directly above portion 11 and in contact therewith, which contact is maintained by the weight of roller 18 and swing frame. In practice the narrow strip of rubber is fed between portion 11 and roller 18 before traveling around the portion 11 and entering between disks 11 and 7, the purpose of roller 18 being to insure uniform feeding of the strip without excessive tension.

Having thus described my invention what I claim is:

1. Apparatus of the character described comprising a roller having a peripheral surface provided with corrugations extending the entire length thereof, a second roller of substantially the same length coacting therewith and having a portion of its surface correspondingly corrugated and another portion of plain cylindrical formation and arranged to coact with the corrugations on said first roller, and means for rotating said rollers in unison.
2. Apparatus of the character described comprising a roller having a corrugated peripheral surface throughout its entire length, a second roller arranged to coact therewith and having side portions provided with corresponding corrugations, and an intermediate plain cylindrical portion arranged to coact with the intermediate corrugated portion of said first named roller, and means for rotating said rollers.
3. Apparatus of the character described comprising a roller having longitudinal corrugations throughout its entire periphery, a second roller arranged to coact therewith and having a portion of its surface pro-

vided with coacting corrugations and another portion of plain cylindrical formation with the periphery thereof at substantially the same distance from the axis of the roller as the periphery of the corrugations.

4. Apparatus of the character described comprising a roller having a corrugated peripheral surface, a second roller arranged to coact therewith and having a portion of its peripheral surface corrugated and an adjacent portion of plain cylindrical formation, one of said rollers being mounted on a swinging axis, and means for rotating said rollers.

5. Apparatus of the character described comprising a roller having a corrugated peripheral surface, a second roller having a portion of its peripheral surface similarly corrugated and having an adjoining portion of its peripheral surface of plain cylindrical formation, and a presser roll bearing on said plain cylindrical portion.

6. Apparatus of the character described comprising a roller journaled on a stationary axis and having a corrugated peripheral surface, a second roller journaled on an axis which is movable toward and from the first named roller and having a portion of its peripheral surface corrugated and an adjoining portion of plain cylindrical formation, and a presser roller mounted on an axis which is movable toward and from the axis of said second roller and having a plain peripheral surface normally contacting with the plain cylindrical portion of the surface of said second roller.

In testimony whereof I affix my signature.

JAMES WILLIAM BRUNDAGE.
